UNITED STATES PATENT OFFICE.

ALFRED L. STREETER, OF CHICAGO, ILLINOIS.

BRAKE-SHOE.

No. 909,704.

Specification of Letters Patent.

Patented Jan. 12, 1909.

Application filed August 10, 1908. Serial No. 447,783.

To all whom it may concern:

Be it known that I, ALFRED L. STREETER, a citizen of the United States, residing at Chicago, Cook county, Illinois, have invented certain new and useful improvements in Brake-Shoes, of which the following is a full, clear, and exact description.

My invention relates to improvements in brake shoes adapted for use upon railway and other cars of like character. One of the difficulties encountered in the use of brake shoes for this purpose lies in the fact that shoes especially constructed for wheels of a given diameter, operate more or less ineffectually on wheels of a different diameter, the different parts are subjected to different degrees of wear, and the shoes are liable to be broken. To meet these difficulties, it is common practice to make the shoe in two separate parts held together by suitable means such as a key or some other connecting device. Brake shoes of this character are objectionable for the reason that the construction is weak, the parts are liable to become separated and lost, and, moreover, it is practically impossible to so mount such two-part brake shoes that the separate parts will receive equal pressure from the brake head and hence be adjusted to equal wear.

My invention is designed to obviate these difficulties and provide a brake shoe which, while formed substantially as a single piece shoe, adapts itself readily to wheels of different diameter whereby all parts of the wear face of the shoe will receive equal wear.

A further object is to provide a flexible brake shoe which shall be capable of as effective operation as a solid or rigid shoe.

A further object is to so form the shoe notwithstanding it may be broken in use, the parts will operate as effectively as a solid shoe and at the same time the shoe will be to a greater degree adapted to conform to wheels of different diameters.

A further object of the invention is to so form and arrange the chilled parts of the shoe that the wear will be equally distributed throughout the wear surface or surfaces.

Preferred embodiments of my invention are illustrated in the accompanying drawings, in which,

Figure 1 is a side elevation of a shoe embodying my invention. Fig. 2 is a cross

section upon the line 2—2 of Fig. 1. Fig. 3 is a detached view of the blank employed to form the lug or lug strap of the brake shoe. Fig. 4 illustrates a modified construction of shoe. Fig. 5 illustrates a second modified form.

In the embodiment of my invention illustrated in Fig. 1, 1 indicates the body of the shoe which has molded therein, a transverse opening 2 making the body of the shoe substantially of two separate parts. Embedded within the back of the shoe is a flexible reinforcing steel strip 3, which in the form shown in Fig. 1, is shouldered or offset at 4 and extends across the upper extremity of 70 the opening 2 at 5. This reinforcing flexible strip serves when the shoe is in use to maintain the divided parts thereof in proper assembled position and serves to transmit the pressure of the brake arm to said parts 75 equally. The lug for receiving the key by which the shoe is secured to its backing consists as here shown of a more or less flexible metal strip 6 having the arms 7 and a central cross piece 8. The arms 7 are bent down 80 as shown in Fig. 1 and are molded in the divided parts respectively of the body portion, the cross piece 8 forming the top of the lug to hold the key in position therein whereby the shoe is held to its backing, the 85 key being inserted in the opening between said cross piece 8 and the portion 5 of the reinforcing strip 3.

In the modified form shown in Fig. 4 the reinforcing strip 9 is shown embedded or 90 molded in the body of the brake shoe and as extended continuously at the same radius over the back of the shoe and over the transverse opening 2 without being offset at this point as shown at 5 in Fig. 1. In this 95 form also is shown a modification of the lug strap 6 in which cross bars 10 are formed between the legs 7 of the strip upon which the reinforcing member 9 rests, whereby the lug strip is securely held within the body 100 of the shoe by the reinforcing strip 9, as well as by being embedded in the shoe. If desired also, other cross bars may be so formed as to extend across above the reinforcing strip 9, whereby the latter also is 105 more firmly held in position, and tendency of the shoe to straighten out is prevented. A further advantage of this last construction also resides in the fact that in the rough usage to which the shoes are subjected in 110

handling, they are less likely to be broken before being placed in position in the brake mechanism.

For the purpose of further reinforcing the shoe against accidental breaking and handling, a reinforcing strip 11 may be molded in the wear face of the two parts of the shoe, and across the transverse opening 2 or in the molding of the shoe a "bridge" 10 or reinforce of cast iron may be cast across the mouth of the transverse opening 2 flush with the wear surfaces of the divided parts of the body portion.

In the modified form shown in Fig. 5, 15 the transverse opening 12 instead of extending entirely through the body portion of the shoe as shown in the form heretofore described, may extend only partially therethrough, leaving a solid portion or bridge 13 between the top of the opening and the reinforcing strip 9, the latter in other respects being the same as shown in Fig. 4 and the lug strap 6 being constructed as heretofore described.

25 In the molding of the shoe and to further equalize the distribution of wear, the parts of the body portion immediately adjacent the transverse opening as at 14 may be chilled or hardened in the same manner as 30 the end portions 15 (Figs. 1 and 5) of the body portion are chilled, the "chill" serving at the same time to form the transverse opening 2 or 12.

When the brake shoe is placed in position 35 in the brake mechanism it is intended that the two parts of the body portion shall be substantially intact. That is to say neither the reinforcing strip 11 (Fig. 4) nor the solid portion 13 (Fig. 5) are broken. When 40 the shoe, however, is subjected to use, and particularly in case the wheels with which it is used are of less diameter than the initial radius of the shoe as a whole, the pressure exerted through the backing and also the 45 wear upon the reinforcing strip 11 (Fig. 4) at the wear surface, will serve to break said reinforcing strip and the solid portion 13, resulting in a substantially two-part shoe, which is securely held together by the reinforcing strips 3 or 9 and by the lug straps 6 and the flexibility of the reinforcing strips 3 or 9, and the lug strap 6 will impart the necessary flexibility to the brake shoe as a 50 whole to enable it at the same time to con- 55 form to the diameter wheel to which it is applied.

While I have here shown several specific constructions of brake shoes embodying my

invention, it is to be understood that the same may be altered in detail without departing from the spirit and scope thereof.

What I claim is:

1. A brake shoe comprising a substantially divided body portion and a flexible reinforcing member connecting the divided 65 parts thereof.

2. A brake shoe comprising a body portion having a transverse opening therein separating said portion into substantially two parts, and a flexible reinforcing mem- 70 ber molded into and connecting the parts of said body.

3. A brake shoe comprising a substantially divided body portion and a lug formed of a flexible metal strip having its opposite 75 extremities molded into the divided parts respectively of said body portion.

4. A brake shoe comprising a substantially divided body portion and a lug formed of a flexible metal strip having its opposite 80 extremities secured to the divided parts respectively of said body portion.

5. A brake shoe comprising a substantially divided body portion, a flexible reinforcing member molded into the back 85 thereof and connecting the divided parts thereof, and a key-receiving lug comprising a flexible strip of metal having its opposite extremities extending down upon either side of said strip and molded into the divided 90 parts respectively of said body portion.

6. A brake shoe comprising a substantially divided body portion, a flexible reinforcing member molded into the back and 95 connecting the divided parts of said body portion, and a second reinforcing and connecting member joining said parts substantially at the wear faces thereof.

7. A brake shoe comprising a body portion having a transverse opening therein 100 forming substantially separate wear faces, a flexible reinforcing member molded into the shoe adjacent said opening and connecting the divided parts thereof.

8. A brake shoe comprising a body por- 105 tion, a transverse opening therein dividing said body portion into substantially two parts, having separate wear faces, said shoe having chilled portions in said wear faces at their outer ends and adjacent said open- 110 ing and having chilled portions in the opposite walls of said opening.

ALFRED L. STREETER.
